CONTAINER FOR A DISPENSABLE PRODUCT
HAVING A PRESSURE RELIEF VALVEArthur L. Hart, Cary, Ill., assignor to American Can
Company, New York, N.Y., a corporation of New
JerseyFiled Mar. 13, 1958, Ser. No. 721,282
4 Claims. (Cl. 222—482)

This invention relates to valves and more particularly to a pressure relief valve for a container.

In many instances, after a container has been sealed, an internal pressure change takes place. For example, when coffee is placed in a container, an amount of carbon dioxide is generated by the coffee which builds up a pressure within the container. It is ideal to provide a device for relieving this generated pressure.

Still a further example of a pressure problem lies in the plastic container having two metal ends covered by United States Patent No. 2,753,088. When this container is used to hold a liquid detergent, particularly when the detergent has an affinity for oxygen, a vacuum is created within the container as the oxygen is absorbed by the detergent. In an extreme case, this vacuum might cause the plastic walls to panel—a term which is used in the trade to indicate a deformation or collapse of the side walls of the container.

It follows that it is a prime object of this invention to provide an improved valve mechanism which will permit the transfer of a fluid relative to the wall of a container to balance pressures without permitting leakage of the contents of the container.

It is a still further object of this invention to provide a one-way valve for equalizing the pressure on opposite sides of the wall of a container.

It is still a further object of this invention to provide an improved one-way valve mechanism.

Numerous other objects and advantages of the invention will be apparent as it is better understood from the following description, which, taken in connection with the accompanying drawings, discloses a preferred embodiment thereof.

With specific reference to the drawings:

FIGURE 1 is a front elevation, partly cut away, showing a valve and container assembly;

FIGURE 2 is an enlarged view of the valving arrangement of FIGURE 1;

FIGURE 3 is a front elevation, partially cut away, showing a second embodiment of the valve and container assembly; and

FIGURES 4 and 5 are enlarged end views of the same position of the valve shown in FIGURE 1 under two conditions of operation.

Briefly this invention relates to a strip of flat flexible and/or resilient material provided with an internal passageway and thus having the configuration of flattened tubing and wherein the passageway communicates with an aperture in the wall of a container. In a preferred form the flattened tubing prevents the escape of the contents of the container and yet permits the admission of fluid from without the container.

With reference to the drawings and particularly FIGURE 1, a container 2 is shown comprising a pair of end walls 4, 6 and a cylindrical body wall 8 hermetically sealed to the end walls. In the illustrated embodiment the body wall 8 is an imperforate plastic tube such as the type described in United States Patent No. 2,753,088.

In the illustrated embodiment, a valve 10 comprises a stem 12, a length of lay flat tubing 14 which is joined at one end to the stem 12 to provide a passage duct therethrough, and which is free at its opposite end. The lay

2

flat tubing is very flexible and in its normal condition its opposite sides are juxtaposed. In this manner any pressure on the opposite sides of the lay flat tubing tends to close the sides tighter and thereby form a seal to prevent the passage of the contents from the inside of the container into stem 12.

The stem 12 is positioned in an aperture 16 formed in a dispensing spout 18. The latter is formed of a resilient material which is snapped in sealed relationship into the dispensing opening 20 of the end wall 4. The dispensing spout 18 has an axial bore 22, and a captive cap 24 connected by a flexible hinge 26 to the body portion of the dispensing spout.

The aperture 16 in dispensing spout 18 is displaced from the axial bore 22 and preferably lies under the hinge 26 which thereby forms a protective covering.

While the stem 12 in the embodiment shown in FIGURE 1 is connected through the aperture 16 in the dispensing spout 18, it is quite apparent it would operate as effectively if it were connected in sealed condition to any other aperture in a container wall, such as the stem 12' shown positioned in the end wall 4' of the container 2' of FIG. 3.

With this construction, after the container has been filled—usually with a hot detergent—and then sealed with the dispensing spout 18, which is closed with the captive cap 24, the valve 10 will operate to balance the internal wall pressure to that of the outside. Specifically as the vacuum is created in the container, due to the cooling of the liquid detergent, or due to the absorption of the oxygen by the detergent, air will pass through the stem 12 of the valve 10 and through the lay flat tubing 14 (now in its FIG. 5 position) into the container.

On the other hand, if the sides of the container are squeezed to dispense the liquid, or if the container is merely inverted, the liquid cannot enter the lay flat tubing 14, since any positive pressure inside the container merely acts to tighten the contact between the two juxtaposed sides of the lay flat tubing 14, as shown in FIG. 4.

It is thought that the invention and many of its attendant advantages will be understood from the foregoing description, and it will be apparent that various changes may be made in the form, construction and arrangement of the parts without departing from the spirit and scope of the invention or sacrificing all of its material advantages, the form hereinbefore described being merely a preferred embodiment thereof.

I claim:

1. A container for a dispensable product, comprising hermetic walls enclosing a product; means defining an aperture in one of said walls; closure means seated in said aperture, said closure means having a direct passage therethrough; and a one-way pressure relief valve which includes a relatively inflexible tubular conduit member received in said passage and directly opening at one end to the atmosphere, and a relatively flexible flat conduit member connected at one-end to the opposite end of said relatively inflexible conduit and directly communicating at its opposite end with the interior of said container, whereby said relatively flexible conduit opens to balance a negative interior pressure with the outside atmospheric pressure to relieve strains on said container walls, and whereby said relatively flexible conduit closes to seal the passage in said closure means against leakage of said product therethrough upon increase of said interior pressure relative to said outside atmospheric pressure.

2. A container for a dispensable product, comprising hermetic walls enclosing a product; means defining an aperture in one of said walls; closure means seated in said aperture, said closure means having a direct passage therethrough; and a one-way pressure relief valve which in-

cludes conduit means selectively communicating the interior of said container with the atmosphere, said conduit means including a relatively inflexible cylindrical portion fixedly received at one end in said passage and a relatively flexible flat tubular portion connected to the opposite end of said cylindrical portion and depending within said container from said one wall thereof, whereby said relatively flexible portion opens to balance a negative interior pressure with the outside atmospheric pressure to relieve strains on said container walls, and whereby said relatively flexible tubular portion closes to seal the passage in said closure means against leakage of said product therethrough upon increase of said interior pressure relative to said outside atmospheric pressure.

3. In a container having a tubular body portion and end walls connected thereto, one of which is apertured to receive a passaged closure member, the improvement which comprises a one-way pressure relief valve, said valve including a first tubular portion insensitive to deformation by pressure fluctuations and firmly seated in said passage in said closure member with one end directly exposed to the atmosphere, said valve further including a flat normally collapsed second tubular portion connected to said first tubular portion and depending within said container in spaced relation to the body portion thereof, whereby said collapsed tubular portion opens to balance a negative interior pressure with the outside atmospheric pressure to relieve strains on said container body portion, and whereby said collapsed tubular portion closes to seal said passage in said closure means against leakage of the container contents therethrough upon increase of said interior pressure relative to said outside atmospheric pressure.

4. A container for a dispensable product, comprising a relatively flexible tubular body portion and a pair of relatively rigid end members connected thereto, one of said end members having a central aperture therein; a closure seated in said aperture and having a product dispensing orifice, said closure adjacent said orifice being provided with a vent passage; and a one-way pressure relief valve which includes a relatively inflexible tubular conduit member received in said passage and directly opening at one end to the atmosphere, and a relatively flexible flat conduit member connected at one end to the opposite end of said relatively inflexible conduit and directly communicating at its opposite end with the interior of said container, whereby said relatively flexible conduit opens to balance a negative interior pressure with the outside atmospheric pressure to relieve strains on said container body portion, and whereby said relatively flexible conduit closes to seal the passage in said closure means against leakage of said product therethrough upon increase of said interior pressure relative to said outside atmospheric pressure.
